(57) **CLAIM**

The ornamental design for an adjustable desk lamp with a clamp, as shown and described.

DESCRIPTION

FIGS. 1 and 2 are first and second perspective views, respectively, of an adjustable desk lamp with a clamp.

FIGS. 3 and 4 are top and bottom views, respectively, of the adjustable desk lamp and clamp.

FIGS. 5 and 6 are right and left side views, respectively, of the adjustable desk lamp and clamp.

FIGS. 7 and 8 are front and back views, respectively, of the adjustable desk lamp and clamp.

FIGS. 9-12 are first perspective, second perspective, right side, and top views, respectively, of the adjustable desk lamp and clamp clamped onto a table shown in broken lines; the table is not part of the claimed design.

FIGS. 13 and 14 are first and second perspective views, respectively, of the adjustable desk lamp and clamp with an optional, mounted, removable remote control shown in broken lines; the remote control is not part of the claimed design.

FIGS. 15 and 16 are top and bottom views, respectively, of the adjustable desk lamp and clamp with the optional, mounted, removable remote control shown in broken lines; the remote control is not part of the claimed design.

FIGS. 17 and 18 are right and left side views, respectively, of the adjustable desk lamp and clamp with the optional, mounted, removable remote control shown in broken lines; the remote control is not part of the claimed design.

FIGS. 19 and 20 are front and back views, respectively, of the adjustable desk lamp and clamp with the optional, mounted, removable remote control shown in broken lines; the remote control is not part of the claimed design.

FIGS. 21 and 22 are first perspective views of the adjustable desk lamp and clamp with the lamp adjusted to differing tilt angles; and,

FIGS. 23 and 24 are first perspective views of the adjustable desk lamp and clamp with the lamp adjusted to differing twist angles.
